US0D1074759S

(12) **United States Design Patent** (10) **Patent No.:** **US D1,074,759 S**
(45) **Date of Patent:** **** May 13, 2025**

(54) **REFRIGERATOR**

(71) Applicant: **Samsung Electronics Co., Ltd.**, Suwon-si (KR)

(72) Inventor: **Yongkeun Choi**, Suwon-si (KR)

(73) Assignee: **Samsung Electronics Co., Ltd.**, Suwon-si (KR)

(**) Term: **15 Years**

(21) Appl. No.: **29/929,113**

(22) Filed: **Feb. 20, 2024**

(30) **Foreign Application Priority Data**

Nov. 10, 2023 (KR) 30-2023-0044520

(51) **LOC (15) Cl.** **15-07**

(52) **U.S. Cl.**

USPC **D15/79**
